US00D629199S

(12) United States Design Patent
Minneman

(10) Patent No.: US D629,199 S
(45) Date of Patent:  *Dec. 21, 2010

(54) SURVIVAL BOX

(75) Inventor: Steven W Minneman, Clayton, OH (US)

(73) Assignee: MTM Molded Products Company, Dayton, OH (US)

() Term: 14 Years

(21) Appl. No.: 29/344,873

(22) Filed: Oct. 6, 2009

(51) LOC (9) Cl. 03-01

(52) U.S. Cl. D3/274; D3/294; D3/203.6

(58) Field of Classification Search D3/20, D3/203.6, 260, 262, 272-274, 281, 291, 301-302, D3/905; 206/315.11, 811; 220/4.21-4.24

(57) CLAIM

The ornamental design for a survival box, as shown and described.

DESCRIPTION

FIG. 1 is a perspective view of an embodiment of my invention;

FIG. 2 is a right side view thereof;

FIG. 3 is a top view thereof, illustrating a compass in the top of the survival box;

FIG. 4 is a left side view thereof;

FIG. 5 is a front view thereof;

FIG. 6 is a rear view thereof; and

FIG. 7 is a bottom view thereof.

FIG. 8 is a perspective view of another embodiment of my invention;

FIG. 9 is a right side view thereof;

FIG. 10 is a top view thereof, illustrating a compass in the top of the survival box;

FIG. 11 is a left side view thereof;

FIG. 12 is a front view thereof;

FIG. 13 is a rear view thereof; and,

FIG. 14 is a bottom view thereof.

The broken lines in the figures depict portions of the design that are included for illustrative purposes only and form no part of the claim.
